UNITED STATES PATENT OFFICE

JOSEPH SACHS, OF WEST HARTFORD, CONNECTICUT

ELECTRIC-CIRCUIT-CONTROLLING APPLIANCE

Application filed November 14, 1929. Serial No. 407,283.

The invention relates particularly to a fused switch appliance of the type disclosed in my patents for Electric circuit controlling appliances, No. 1,754,443 issued April 15, 1930 and No. 1,754,445 issued April 15, 1930, and in my copending application and for Electric meter service appliance, Serial No. 247,730 filed January 18, 1928.

In each of the above mentioned patents and application I have disclosed a fused switch appliance wherein there is provided for each leg of the circuit two separate pairs of stationary switch contacts connected in series with each other so that the circuit is broken at four separate places. A switch appliance having provision for breaking the circuit at four or more places is highly advantageous for the reasons as set forth in the aforesaid applications, but for certain classes of service, wherein the switch is operated only infrequently, I have found that it is entirely satisfactory to provide only a single pair of stationary contacts, thus providing for the breaking of each leg of the circuit in two places only. By providing a two break switch instead of a four break switch, considerable economy of manufacture and installation is effected, while retaining many of the advantages incident to switches of the type set forth in the said patents and application.

One object of the present invention is to provide a switch similar in general principles to those set forth in the aforesaid patents and application, but having certain novel features of construction which make possible the economy and simplicity incident to the provision of only one pair of stationary switch contacts, without, however, sacrificing other advantageous features.

Another object of the invention is to provide an improved location and mounting for the wire terminals for the neutral connection through the appliance.

Further objects of the invention will be apparent from the following specification and claims.

The present invention is particularly applicable to a meter service switch, which, as is well known, is ordinarily required to be operated only infrequently. Such a switch

is shown in the accompanying drawings, but it will be understood that I do not necessarily so limit myself. It will be further understood that the drawings are intended for illustrative purposes only and are not to be construed as defining or limiting the scope of the invention, the claims forming a part of this specification being relied upon for that purpose.

Of the drawings:

Fig. 1 is a perspective view of a meter service installation embodying the invention, the front cover being broken away to show interior parts.

Fig. 2 is a front view of the fused switch appliance, the upper and lower portions of the enclosing cabinet being broken away.

Fig. 3 is a bottom view of the parts shown in Fig. 2, this view being partly in section along the line 3—3 of Fig. 2.

Fig. 4 is a fragmentary side view of the parts shown in Fig. 2, certain portions of the enclosing cabinet being shown in section.

Fig. 5 is a vertical sectional view taken along the line 5—5 of Fig. 3 and omitting the cabinet and operating spindle.

Fig. 6 is a bottom view similar to Fig. 3, but showing the base detached from the other parts.

In the embodiment of the invention shown in the drawings, there are two pairs of fuse contacts and two separate switching devices, but it will be understood that the invention is not necessarily limited to any particular number of fuses and switches. The fuse and switch contacts and also the meter testing means are shown symmetrically disposed with respect to the vertical central plane of the appliance, and for the sake of convenience and simplicity of description, I will describe in detail only those parts on one side of the said plane, it being understood that the parts on the other side are, or may be, the same in construction except for reversal of positions.

Fuse receiving contacts 1 and 2 are provided on the front face of an insulating base 3, and means are provided for supporting the base 3 in fixed spaced relationship to a rear support. When there is an enclosed cabinet

this support may be the rear wall of the cabinet. The fuse contacts as shown are adapted for receiving a cartridge enclosed fuse such as F, but it will be understood that the invention is not limited for use with fuses of this particular type.

In addition to the main rear support, I provide an independent insulating supporting device which is ordinarily secured to the main rear support but which is nevertheless separate therefrom. This supporting device is shown at 4 in the drawings and it may consist of a single transverse bar of insulating material. The fuse contacts and the base are normally held in fixed spaced relationship with the supporting device 4.

Preferably, a plurality of supporting elements are provided which are connected at their forward portions with the base and at their rear portions with the rear supporting device 4. The said elements therefore serve to support the fuse contacts and the base in the described relationship with the said supporting device. As shown, there is one such supporting element for each pair of fuse contacts, this being represented at 5. The supporting element 5 is shown as being Z-shaped (See Figs. 2, 3 and 6), and it has its rear portion connected with the supporting device 4 by means of screws 6 and 6^a. Suitable means such as a screw 7 is provided for mechanically connecting the forward portion of the supporting element with the fuse base 3. The screw 7 preferably also serves to electrically connect the fuse contact 1 with the supporting element 5. A similar screw 7^a serves to hold the fuse contact 2 in place.

Located at least in part in the space behind a vertical plane extending through the rear parts of the base 3 is a switching device comprising a pair of stationary switch contacts 8 and 9. Preferably one of the said switch contacts, that is the contact 8, is mounted directly upon and electrically connected with the supporting element 5, which element is electrically connected with the fuse contact 1 as already stated. A contact supporting element 10 is provided for the switch contact 9, this preferably being similar to the main supporting element 5 and being similarly secured to the supporting device 4 by screws 11 and 11^a. Connected with the supporting element 10 is a wire connecting terminal 12. I have shown a terminal of the solder lug type, but I do not so limit myself.

Each of the two contacts 8 and 9 is formed of resilient sheet metal and preferably has two U-shaped bends, as set forth in detail in my patent for Electric circuit controlling appliance, No. 1,754,446 issued April 15, 1930. The two contacts 8 and 9 are oppositely disposed and are respectively connected mechanically and electrically with two supporting elements 5 and 10 as already stated.

For establishing or breaking electrical con-

nection between the switch contacts 8 and 9 I provide a switching member which is rectilinearly movable substantially parallelly with the front face of the supporting device and with the rear face of the fuse base. The switching member comprises an insulating element 13, and a conducting contact element 14 carried thereby. The insulating element 13 is preferably in the form of a flat plate, and the said conducting contact element 14 extends through it and projects somewhat beyond the opposed surfaces thereof as shown. The switching member may be similar in construction to that shown in my said patent No. 1,754,443. When the stationary switch contacts are located as shown, the said flat insulating element 13 is arranged perpendicularly to the supporting device and to the fuse base. The said element may extend into a groove 15 formed in the base 3. From the foregoing description, it will be apparent that when the switching member is in the "on" position as shown, a circuit will be established from the wire connecting terminal 12 through the contact supporting element 10 and the switch contacts 9, 14 and 8 to the supporting element 5 and thence to the fuse contact 1.

I have shown an enclosing cabinet 16 of sheet metal having a rear wall 17, side walls 18, 18 and end walls 19 and 20. The upper end wall 19 preferably has an opening therein which adapts the cabinet for direct protective relationship with an electric meter such as M. The cabinet has an openable front cover 21, which is shown as being hinged at 21' to the bottom end wall 20.

As already explained, the base 3 with the fuse contacts 1 and 2 thereon, is supported in part upon the transverse insulating supporting device or bar 4 by means of the two supporting elements 5, 5. When the fused switch proper is mounted in an enclosing cabinet, as is ordinarily preferred, the supporting device 4 is directly fastened to the rear wall 17 of the cabinet by means of screws 22, 22. I provide other supporting means for the base preferably adapted to directly engage the rear supporting wall 17. While I do not so limit myself, I have shown spacing tubes 23, 23 which extend horizontally between the rear wall and the base, the tubes preferably extending into suitable recesses in the rear of the base. Long screws 24, 24 are provided which extend through holes in the base and through the spacing tubes 23, 23 and which have threaded engagement at their rear ends with the supporting wall 17. From the foregoing description it will be apparent that the base 3 is supported in part upon the supporting element 4 and in part substantially directly upon the main rear supporting wall 17.

The switching members are guided and held in place at the front by means of the

base 3, and they are guided in part at the rear by means of the supporting device 4. The said members are further guided at the rear by means of the rear cabinet wall 17, each insulating element 13 having a rearward projection or extension 13' which has sliding contacts with the said wall. Although the switching members are guided by the base 3, the supporting device 4 and the wall 17 and held by these parts against forward or backward movement, each of them is entirely free to adjust itself laterally to conform to the positions of the corresponding stationary switch contacts.

For operating the switching members there is provided a spindle 25 having two pivot sections 26 and 27 extending through bearing openings in the side walls 18, 18 of the cabinet. The said spindle is bent to form a manually operable handle 28 outside of the cabinet and also to form a crank section 29 inside of the cabinet and between the pivot sections. In each insulating element 13 there is a slot 30 adapted to receive the crank section 29. The slot 30 is preferably open at one end, that is, at the back end, so as to facilitate assembly or disassembly of the fused switch unit to or from the cabinet. By moving the handle 28 each of the switch members can be moved longitudinally upward or downward, as desired. With the handle 28 in its uppermost position as shown in Fig. 1, the switching members will be held in their lowermost positions thus completing the circuit through the switch and fuse contacts as described. When the handle 28 is moved to its lowermost position, the switching members will be moved to their uppermost positions, as shown by dot-and-dash lines in Fig. 4, thus separating the movable contacts 14 from the stationary contacts 8 and 9 and thus breaking each leg of the circuit at two places as already fully described.

The supporting device 4 together with the base 3 and all of the parts directly carried thereby constitute a unit which may be assembled with or disassembled from the enclosing cabinet. The open ended slots 30 in the insulating elements of the switching members make it possible for the said switch members to be readily engaged with or disengaged from the cranked section 29 of the operating spindle.

While the reciprocating switching members may ordinarily be regarded as constituting parts of the removable fused switch unit, they are nevertheless easily removable therefrom or assembled therewith when the unit is separate from the cabinet and operating spindle. This will be apparent from an inspection of Fig. 5 which shows in dot-and-dash lines an intermediate position which is assumed by each switching member as it is assembled with or removed from the other parts of the fused switch unit.

It will be apparent that the base with the fuse contacts thereon is readily detachable without disturbing the switch contacts. The base may be removed as shown in Fig. 6, by loosening the screws 7, 7 and 24, 24. Removal of the base permits more complete access to the switch parts for inspection, cleaning or adjustment. Inasmuch as the reciprocating switching members are guided and held in place at the front by means of the base, it will be apparent that when the base is removed, the said switching members may also be independently removed in the forward direction.

In order that access may be had to the fuses when the main front cover 21 of the cabinet is closed, the said cover is provided with an opening therein through which the fuses are accessible. In order to prevent access to the fuses through the said opening except when the circuit is broken there is provided an auxiliary cover 31 which is so related to the handle that the cover can be opened only when the handle is in switch opening position and so that the handle cannot be moved to switch closing position when the cover is open. The details of the cover and handle construction form no part of the present invention being covered by my patents for Enclosed fused switches, Nos. 1,721,493, 1,721,494 and 1,721,495, all issued July 16, 1929.

For an appliance of the character described, it may be desired to provide a non-fused and non-switching connection for the wires constituting the neutral leg of the circuit. For the sake of simplicity and convenience I provide terminals for the neutral wires mounted directly upon the before-mentioned insulating supporting device 4. When the appliance is adapted for use with a three wire circuit, the neutral terminals may be located at or near the center between the stationary switch contacts of the two pairs. I have shown the supporting device 4 as provided with a central forward extension 4'. Mounted on this extension are two wire terminals 32 and 33 which are electrically connected together, being held in place by a screw 34 and nut 34'.

In addition to the parts already described, I may provide means for facilitating the testing of the meter. The details of the testing means may be varied according to the conditions of use. For three wire service I preferably provide testing means for each of two legs of the circuit, each means comprising at least one movable test link adapted to be included in the circuit between the meter and the load wires and adapted to be so moved as to disconnect the meter from the load wires while testing is being carried on. The testing means for the respective legs are preferably located at the sides of the base 3 on lateral extensions 3', 3' formed thereon.

Ordinarily and preferably, the incoming circuit wires S, S are connected with the terminals 12, 12 and as shown a neutral wire S' is connected with the terminal 32. The circuit extends from the terminals 12, 12, through the switch and fuse parts in the manner already described to terminals 35, 35 on the base extensions 3', 3', preferably near the tops thereof. The said terminals 35, 35 are indirectly connected with the outgoing or load circuit wires through the meter M, connections C¹ and C² extending from the said terminals 35, 35 to the meter. Other meter connections C³ and C⁴ extend from the meter M to wire connecting terminals 36, 36 mounted on the extensions 3', 3' adjacent the terminals 35, 35. The outgoing circuit or load wires L, L are connected with terminals 37, 37 on the base extensions 3', 3', and the neutral load wire L' is connected with the terminal 33. The said terminals 37, 37 are connected respectively with the terminals 36, 36 by means of movable testing links 38, 38. As illustrated the links 38, 38 are entirely removable, but this is not essential. The testing links 38, 38 as shown are of a well known construction, each link being slotted near its ends and thus adapted to receive studs 39 and 40 connected respectively with the corresponding terminals 36 and 37. Each link has an insulating handle 38'. It will be seen that by removing the links 38, 38 the circuit may be broken between the said terminals 36, 36 and 37, 37.

Preferably, in addition to the testing links 38, 38 I provide other similar links 41, 41 interposed between the fuse contacts 2, 2 and the terminals 35, 35. At the back of the base at the side thereof is located a transverse conductor strap 42. At the inner end each strap is engaged by the screw 7^a which holds the fuse contact 2 in place, the screw serving as an electrical connection between the contact and the strap. At the outer end each strap is engaged by a screw or stud 43. The corresponding testing link 41 is connected with the stud 43 and with a similar stud 44 connected with the terminal 35.

In addition to the removable links 38, 38 and 41, 41 I provide contacts adapted for the attachment of by-passing connections from the fuse contacts 2, 2 to the terminals 37, 37. For this purpose, I provide at each side studs 45 and 46 electrically connected respectively with the strap 41 and the terminal 37. Links 47, 47 may be provided as shown in dot-and-dash lines in Fig. 3 for connecting the said studs 45, 45 and 46, 46. It will be seen that when the links 47, 47 are in place, the circuit will extend directly through the switch and fuse to the load terminals 37, 37. It is then possible to either partly or entirely disconnect the meter and electrically free the terminals thereof by re-

moving some or all of the links 38, 38 and 41, 41.

The several studs 39, 40, 43 and 44 are adapted to serve as test contacts for the attachment of instrument leads and the like which may be needed for the purpose of testing the meter. Preferably a test contact 48 is connected with the neutral terminals 32 and 33 for a similar purpose.

What I claim is:—

1. In a fused switch appliance, the combination of a rear insulating supporting device adapted to be secured to a rear supporting wall, an insulating base in front of the supporting device and spaced therefrom, means carried by the supporting device and serving to partly support the base, other means adapted to directly engage the rear supporting wall and also serving to partly support the base, a pair of fuse contacts on the base, a pair of stationary switch contacts at the front of the supporting device and behind the plane of the rear face of the base, one of them being normally electrically connected with one of the fuse contacts, and a switching member rectilinearly movable between the said switch contacts and parallelly with the rear face of the base, the said member comprising an insulating element and a contact element carried by the insulating element and having contact faces respectively adapted upon rectilinear movement to engage and disengage the stationary switch contacts to make and break electrical connection between them.

2. In a fused switch appliance, the combination of a rear insulating supporting device adapted to be secured to a rear supporting wall, an insulating base in front of the supporting device and spaced therefrom, means carried by the supporting device and detachably connected with the base for partly supporting it, other means serving to detachably connect the base with the rear supporting wall, a pair of fuse contacts on the base, a pair of stationary switch contacts at the front of the supporting device and behind the plane of the rear face of the base, one of them being normally electrically connected with one of the fuse contacts, and a switching member rectilinearly movable between the said switch contacts and parallelly with the rear face of the base, the said member comprising an insulating element and a contact element carried by the insulating element and having contact faces respectively adapted upon rectilinear movement to engage and disengage the stationary switch contacts to make and break electrical connection between them.

3. In a fused switch appliance, the combination of a rear insulating supporting device adapted to be secured to a rear supporting wall, a pair of stationary fuse contacts carried at least in part by the supporting device and spaced forward therefrom, a pair of

stationary switch contacts carried directly by the supporting device adjacent the front face thereof and behind a plane through the rear parts of the fuse contacts, one of the switch contacts being normally electrically connected with one of the fuse contacts, and a switching member rectilinearly movable behind the said plane through the rear parts of the fuse contacts and having guiding engagement at the rear with the supporting device and also with the rear supporting wall, the said switching member being adapted upon rectilinear movement to engage and disengage at least one of the stationary switch contacts to make and break electrical connection between them.

4. In a fused switch appliance, the combination of a rear insulating supporting device adapted to be secured to a rear supporting wall, a base carried at least in part by the supporting device and spaced forward therefrom, a pair of stationary fuse contacts on the base at the front thereof, a pair of stationary switch contacts carried directly by the supporting device adjacent the front face thereof and behind the plane of the rear face of the base, one of the switch contacts being normally electrically connected with one of the fuse contacts, and a switching member rectilinearly movable behind the said plane through the rear parts of the fuse contacts and having guiding engagement at the front with the base and at the rear with the supporting device and also with the rear supporting wall, the said switching member being adapted upon rectilinear movement to engage and disengage at least one of the stationary switch contacts to make and break electrical connection between them.

5. In a fused switch appliance, the combination of a rear insulating supporting device adapted to be secured to a rear supporting wall, a pair of stationary fuse contacts carried at least in part by the supporting device and spaced forward therefrom, a pair of stationary switch contacts carried directly by the supporting device adjacent the front face thereof and behind a plane through the rear parts of the fuse contacts, one of the switch contacts being normally electrically connected with one of the fuse contacts, a switching member rectilinearly movable behind the said plane through the rear parts of the fuse contacts and adapted upon rectilinear movement to engage and disengage at least one of the stationary switch contacts to make and break electrical connection between them, and two electrically connected wire terminals on the supporting device electrically separate from the said switch contacts and adapted for the separate attachment of two wires forming a neutral circuit connection.

6. In a fused switch appliance, the combination of a rear insulating supporting device adapted to be secured to a rear support-

ing wall, two transversely spaced pairs of stationary fuse contacts carried at least in part by the supporting device and spaced forward therefrom, two transversely spaced pairs of stationary switch contacts carried directly by the supporting device adjacent the front face thereof and behind a plane through the rear parts of the fuse contacts, one of the switch contacts of each pair being normally electrically connected with one of the fuse contacts of the corresponding pair, two switching members rectilinearly movable behind the said plane through the rear parts of the fuse contacts, the said switching members being each adapted upon rectilinear movement to engage and disengage at least one of the stationary switch contacts of the corresponding pair to make and break electrical connection between them, and two electrically connected wire terminals on the supporting device between the two pairs of switch contacts, the said terminals being electrically separate from the said switch contacts and being adapted for the separate attachment of two wires forming a neutral circuit connection.

In testimony whereof I have hereunto set my hand this 12th day of November, 1929.

JOSEPH SACHS.
